Primary Examiner — Stella Reid*Assistant Examiner* — Elizabeth J Oswecki*(74) Attorney, Agent, or Firm* — Cynthia R. Miller(57) **CLAIM**

The ornamental design for a fragrance bottle cap, substantially as shown and described.

DESCRIPTION

FIG. 1 is a top, front and right side perspective view of a first embodiment of my new design for a fragrance bottle cap; FIG. 2 is a front elevation view of the fragrance bottle cap shown in FIG. 1, the rear elevation view being a mirror image thereof;

FIG. 3 is a top plan view of the fragrance bottle cap shown in FIG. 1;

FIG. 4 is a bottom plan view of the fragrance bottle cap shown in FIG. 1;

FIG. 5 is a side elevation view of the fragrance bottle cap shown in FIG. 1, the opposite side being a mirror image thereof;

FIG. 6 is a top, front and right side perspective view of a second embodiment of my new design for a fragrance bottle cap;

FIG. 7 is a front elevation view of the fragrance bottle cap shown in FIG. 6, the rear elevation view being a mirror image thereof;

FIG. 8 is a top plan view of the fragrance bottle cap shown in FIG. 6;

FIG. 9 is a bottom plan view of the fragrance bottle cap shown in FIG. 6; and,

FIG. 10 is a side elevation view of the fragrance bottle cap shown in FIG. 6, the opposite side being a mirror image thereof.
